UNITED STATES PATENT OFFICE.

FREDERICK C. SHEARER, OF EAGLE PASS, TEXAS, ASSIGNOR TO U. S. INDESTRUCTIBLE TIE MANUFACTURING COMPANY, OF EAGLE PASS, TEXAS, A CORPORATION OF TEXAS.

RAILWAY-TIE.

1,229,154.

Specification of Letters Patent.

Patented June 5, 1917.

Application filed December 29, 1915. Serial No. 69,239.

To all whom it may concern:

Be it known that I, FREDERICK C. SHEARER, a citizen of the United States, residing at Eagle Pass, in the county of Maverick and State of Texas, have invented certain new and useful Improvements in Railway-Ties; and I do hereby declare the following to be a full, clear, and exact description of the invention, such as will enable others skilled in the art to which it appertains to make and use the same.

This invention relates to new and useful improvements in railway ties and the principal object of the invention is to provide a tie which is adapted to be constructed of reinforced concrete or any other suitable material.

Another object of the invention is to provide a tie having a cushioning block which may be made of wood or compressed fiber so as to provide a resilient seat for the rails.

Still another object of the invention is to provide a novel form of rail plate and rail attaching means therefor.

25 A further object of the invention is to provide a tie having its under side recessed to insure the proper seating of the same in the road bed.

With these and other objects in view, the invention consists in the novel combination and arrangement of parts which will be fully set forth in the following specification and accompanying drawings, in which:

Figure 1 is a side view in elevation of a tie constructed in accordance with this invention showing the rails in place thereon.

Fig. 2 is a fragmentary top plan view of one end of the tie showing the rail partly in section to more clearly illustrate the details of construction.

Fig. 3 is an enlarged longitudinal sectional view on line 3-3 of Fig. 2.

Fig. 4 is a transverse sectional view on line 4-4 of Fig. 1, and

Fig. 5 is a horizontal sectional view on line 5-5 of Fig. 3.

Referring to the drawings the numeral 1 designates as an entirety the body of the tie comprising a pair of enlarged end members 2 connected by a reduced portion 3. A suitable longitudinally extending V-shaped rib 4 extends downwardly from the reduced portion 3 and the lower edge thereof lies flush with the lower faces of the portions 2 hereinbefore referred to. Each of the end

members or portions 2 is provided with a transversely extending recess 5 adapted for the reception of the cushioning blocks and formed at opposite terminals of the recesses 5 and in the opposite faces of the members 60 2 are the depressions 6, the use of which will appear as the description proceeds.

Seated in the recesses 5 are the cushioning blocks 7 having extending therethrough the transverse apertures 8 through which suitable bolts 9 pass and these bolts extend through openings formed in the bars 10 which extend longitudinally of the tie on opposite sides thereof and are adapted to seat in the depressions 6 as clearly shown in Fig. 5.

Formed in the upper face of each of the members 2 is a longitudinally extending central groove 11, the inner end of which communicates with the recess 5, and seated in this groove is the tongue 12 of the rail plate 13. This rail plate 13 is of a size sufficient to extend substantially entirely across the cushioning blocks and is formed near one end with an opening 14 through which the spikes 15 extend. The opposite end of the plate is bent upwardly as at 17 to form an abutment for the rail clamp 18 provided at its inner end with the flange engaging portion 19. The rail engaging portion and tongue 12 are formed with alining openings through which the bolts 20 extend and these openings register with suitable openings 21 formed in the enlarged portion of the tie as clearly shown in Fig. 3.

It is to be understood that the tie is provided with suitable longitudinally extending reinforcing bars 21 the opposite ends of which are bent upwardly as at 22 while the central portions are arched as at 23 to conform to the shape of the under side of the reduced portion 3 of the tie.

It will be apparent from the foregoing that in use the tie is used in the ordinary manner and the rails seated on the plates 100 13. The plates are then placed so that the flanges 17 abut the end of the recesses 11 and the bolts 20 are then passed upwardly through the openings in the tie and plates and the rail clamp 18 is then slipped in place and held by the nuts on the bolts. The spike 15 is then driven through the opening 14 and it will be seen that the rail will be firmly clamped against the cushioning block and held against accidental move- 110

ment. It will also be seen that the cushioning block may be turned so that various faces may be presented upwardly thereby taking up any wear thereon and increasing 5 the life of the block.

While in the foregoing there has been shown and described the preferred embodiment of this invention, it is to be understood that such changes may be made in the 10 combination and arrangement of parts as will fall within the spirit and scope of the appended claim.

What is claimed is:—

The combination with a railroad tie having 15 cushion receiving chambers near opposite ends and being provided with recesses in its upper side communicating with said

cushion receiving chambers, of blocks seated in said cushion receiving chambers, tie plates seated on the blocks and extending 20 into the recesses, the outer ends of the tie plates being upturned and engaging the outer ends of the recesses to prevent the tie plates from moving outwardly, bolts extending through the ties and tie plates and 25 clamp plates seated on the tie plates and engaging the upturned portions, said clamp plates being held in place by the bolts.

In testimony whereof I affix my signature in presence of two witnesses.

FREDERICK C. SHEARER.
